UNITED STATES PATENT OFFICE.

COSMO LIACI, OF NEW HAVEN, CONNECTICUT, ASSIGNOR OF ONE-FOURTH
TO RAFFAELE GAGHAIDI, ONE-FOURTH TO LIAGI COLAVECCHIO, AND
ONE-FOURTH TO EGIDIO FERRAINOLO, OF NEW HAVEN, CONNECTICUT.

WRENCH.

No. 822,962.

Specification of Letters Patent.

Patented June 12, 1906.

Application filed February 8, 1906. Serial No. 299,350.

To all whom it may concern:

Be it known that I, COSMO LIACI, a citizen of the United States, residing at New Haven, in the county of New Haven and State of Connecticut, have invented a new and useful 5 Wrench, of which the following is a specification.

This invention relates to wrenches for turning nuts, pipes, and other articles, and 10 has for its principal object to provide a wrench of simple and economical construction in which the jaws are connected to the operating-handle by a ratchet or similar mechanism, means being provided for rendering the ratchet effective in either direction 15 of movement and for locking the jaws rigidly to the handle, so that the tool may be used in the ordinary manner.

A further object of the invention is to provide 20 mechanism of simple construction and which may be quickly adjusted for the purpose of altering the direction of rotative movement and for rigidly locking the parts.

A still further object of the invention is to 25 simplify and improve the construction of wrench and to provide a centering or holding device by which the jaw end of the tool may be held in position by one hand, while the operating-handle is manipulated by the other 30 hand.

With these and other objects in view, as will more fully hereinafter appear, the invention consists in certain novel features of construction and arrangement of parts hereinafter fully described, illustrated in the 35 accompanying drawings, and particularly pointed out in the appended claims, it being understood that various changes in the form, proportions, size, and minor details of the 40 structure may be made without departing from the spirit or sacrificing any of the advantages of the invention.

In the accompanying drawings, Figure 1 is a 45 sectional elevation of a wrench constructed in accordance with the invention. Fig. 2 is an inverted plan view of the upper detachable plate, showing the stem in section. Fig. 3 is an inverted view of the handle portion of the wrench with the lower plate removed 50 and showing the stem in section. Fig. 4 is a plan view of the main portion of the handle with the top plate removed. Fig. 5 is a transverse sectional view of the wrench.

Similar numerals of reference are employed to indicate corresponding parts throughout 55 the several figures of the drawings.

The handle is preferably formed of three sections 10, 11, and 12, the section 10 being extended rearward and provided with one or more grips 13. The forward end of the main 60 section 10 is recessed on both of its faces and is provided on one side with pins 14 and 15, which enter suitably-located openings in the third member or cover-plate 12. All three of the members are provided with alining 65 openings for the reception of two ratchet-wheels 18 and 19, the teeth of which face, respectively, in opposite directions, and said ratchet-wheels have alined openings for the reception of a non-circular stem 20, the upper 70 end of which is rigidly secured to the jaw members of the wrench.

Within the lower recessed portion of the member 10 is arranged a pawl 21, one end of which is pressed into engagement with the 75 teeth of the ratchet-wheel 18 by means of a spring 22. This pawl is pivotally mounted on the pin 17, and its rear or tail end is engaged by the cam-shaped end of a rack-bar 23, that is guided within a suitable groove 80 formed near one edge of the handle member 10. The teeth of this rack-bar are engaged by the teeth of a pinion 25, mounted on a spindle that extends upward through the upper plate 11 and carries a knob or disk 26, 85 which may be turned for the purpose of moving the rack-bar to and fro, and thus moving the pawl 21 from engagement with the ratchet-wheel or permitting the spring 22 to force said pawl into engagement with the 90 ratchet-wheel. Arranged within the upper recess of the central member 10 are a number of ribs 28, 29, and 30, all of which are disposed in parallel relation, and between the side of the member 10 and the rib 28 is mounted a 95 rack-bar 31, having a cam-shaped end that is adapted to engage a pawl 32, pivoted on the pin 14 and arranged to engage with the teeth of the ratchet-wheel 19, said pawl being pressed in the direction of the teeth by a suitable spring 33. The teeth of the rack-bar 31 are engaged by the teeth of a pinion 35, having a spindle 36, that projects upward through an opening formed in the upper section 11 and which carries a head or disk 37, 105 that may be turned for the purpose of mov-

ing the pawl 32 from engagement with the ratchet-wheel 19 or permitting the spring 33 to force said pawl into engagement with said ratchet-wheel. These two mechanisms serve 5 as a ready means for controlling the effective rotative movement of the jaw members, so that the handle may be operated for the purpose of turning the jaws in either direction.

Guided between the ribs 29 and 30, which 10 are formed also in the upper section 11 of the handle, is a rack-bar 39, the forward end of which is provided with a rectangular recess 40, that is adapted to engage the non-cylindrical stem 30 and lock the same from movement, so that when moved to stem-engaging 15 position the jaws and the handle will be rigidly locked to each other, so that the wrench may be used in the same manner as an ordinary monkey-wrench. The teeth of the rack-bar 20 39 are engaged by the teeth of a pinion 41, having a stem 42, that extends upwardly through an opening formed in the upper member 11 of the handle and carries a small knob or disk 43, which may be turned in order 25 to move the stem-locking bar to or from operative position. The upper end of the stem is provided with an enlarged head 50, having laterally-extended wings arranged diametrically opposite each other, and these 30 wings carry upwardly-projecting lugs 51, that are adapted to fit within corresponding recesses formed in the lower face of the shank 53 of the main or relatively fixed jaw 54.

The shank 53 is provided with a longitudinal 35 groove for the reception of the reduced lower end of the movable jaw 56, and this reduced lower end of the movable jaw has a threaded opening for the passage of an adjusting-screw 57, both ends of which are 40 loosely mounted in the shank of the fixed hub, the inner end of the screw having a suitable knob 58, which may be turned for the purpose of adjusting the distance between the jaws in accordance with the size of the object being operated upon.

The lower end of the square stem 50 is reduced and threaded for the reception of a handle 60, the upper portion of the handle being flared out to form a disk 61, so that it 50 may be conveniently grasped in the hand for the support of the jaw end of the wrench while the handle proper is manipulated by the other hand.

I claim—

55 1. In a wrench, a recessed handle, a pair of ratchet-wheels provided with non-circular openings, the teeth of said ratchet-wheels facing, respectively, in opposite directions, a stem extending through the openings, clamp- 60 ing-jaws supported by the stem, pawls engaging the ratchet-wheels, springs tending to

force said pawls to operative position, rack-bars arranged within the recesses of the handle and having cam-shaped ends for engagement with the tails of the pawls, pinions engaging said rack-bars, and nuts or disks arranged outside the handle for turning said pinions. 65

2. In a wrench, the combination with a recessed handle member, of a pair of ratchet-wheels having non-circular openings, the teeth of said ratchet-wheels facing, respectively, in opposite directions, a stem extending through said openings, jaws supported by the stem, pawls arranged to engage said ratchet-wheels, means for controlling the movement of the pawls to operative and inoperative positions, and an adjustable means within the handle for engaging the stem and locking the same rigidly to said handle. 70 75

3. In a wrench, the combination with a recessed handle, of ratchet-wheels supported therein and provided with non-circular openings, the teeth of said ratchet-wheels facing, respectively, in opposite directions, a stem extending through the openings, jaws supported by the stem, pawls for engaging the ratchet-wheels, means for adjusting the pawls to operative and inoperative positions, a rack-bar provided within the recessed handle, and having at one end a non-circular recess 80 to engage and interlock with the stem, a pinion engaging said rack-bar, and means for operating said pinion. 85 90

4. In a wrench, the combination with a sectional handle having recesses, and provided 95 with a plurality of parallel ribs within the recesses, there being an opening extending through all of the sections of the handle, a pair of ratchet-wheels arranged within said opening and having their teeth facing, respectively, in opposite directions, said ratchet-wheels being provided with non-circular openings, a stem extending through the openings of the ratchet-wheels, clamping-jaws carried by said stem, pawls for engagement with the 100 ratchet-wheels, a locking-bar for engagement with the stem, a rack carried by the locking-bar, rack-bars having cam-shaped ends for engagement with the tails of the pawls, all of 105 said racks being guided by the ribs within the recessed portions of the handle, pinions for engagement with said racks and provided with spindles that extend to the outside of the handle, and operating knobs or disks secured to said spindles. 110 115

In testimony that I claim the foregoing as my own I have hereto affixed my signature in the presence of two witnesses.

COSMO LIACI.
